JAR CAP TOOL

Michelangelo Di Grappa, East Palestine, Ohio

Application November 29, 1937, Serial No. 177,108

2 Claims. (Cl. 81—15.1)

This invention appertains to new and useful improvements in implements for reforming and cleaning jar caps especially of the Mason jar type.

The principal object of the present invention is to provide means whereby jar caps can be reformed at their packing engaging edges in a quick and simple manner without any strain or effort on the part of the operator.

Another important object of the invention is to provide an implement of the character stated which will in use serve to hold a jar cap firmly while being treated.

Still another important object of the invention is to provide a cap appliance of the character stated whereby the interior of a jar cap can be cleaned of any scum or other foreign matter in a rapid and efficient manner.

These and various other important objects and advantages of the invention will become apparent to the reader of the following specification.

In the drawings:

Figure 1 represents a side elevational view of the apparatus with handles of the reformer in section.

Figure 2 is a top plan view of the device.

Figure 3 is a face elevational view of the chuck.

Figure 4 is a back side elevational view of the chuck.

Figure 5 is a fragmentary side elevational view of the reformer showing a portion of a cap in section.

Figure 6 is a fragmentary end elevational view showing the manner in which the reformer and cleaner are mounted.

Figure 7 is a fragmentary detailed sectional view taken substantially on the line 7—7 of Figure 5.

Referring to the drawings wherein like numerals designate like parts, it can be seen in Figure 1, that numeral 5 represents a substantially rectangular base which can be supplemented with the provision of suitable clamp means whereby the base can be secured to a table or the like.

A bearing bracket 6 preferably of sheet metal is suitably secured to the base 5 adjacent one end thereof and formed at its upper end to provide a sleeve bearing 7 in which the shaft 8 is journaled in the longitudinal center of the base. One end of the shaft 8, constituting the rear end, is provided with a crank handle 9 whereby the shaft 8 and the chuck generally referred to by numeral 10 may be rotated.

The chuck 10 includes an elongated substantially rectangular plate 11 suitably secured at its

center, as by welding, (not shown) to the front end of the shaft 8 diametrically thereof. A pair of substantially semi-circular clamping wings 12 are pivotally mounted at one end thereof, as at 13, on one end of the plate 11 in edge to edge relation for swinging movement toward and from each other into and from clamping relation, respectively. A pair of semi-circular clamping flanges 19 are provided on the wings 12, respectively, for cooperation to grip therebetween a jar cap 20 under movement of said wings toward clamping relation. The flanges 19 are arranged to form, in the limit of clamping movement of the wings 12, a diametrically split circle partially surrounding the cap 20 in spaced relation to the usual edge flange A thereof so that said flange is free.

The wings 12 are movable into and from clamping relation through the medium of a plate-like slide 14 spanning the plate 11 at one side of the shaft 8 and guided by plate 11 for movement lengthwise thereof by side flanges 14' engaging the side edges of said plate 11. A pair of ears 15 extend from opposite flanges 14', respectively, flat against the wings 12. A pair of angularly related cam slots 16 in said ears 15 and screws 17 passing through said slots into the wings 12, provide for movement of said wings into and from clamping relation under movement of said slide in opposite directions, respectively. A hand grip 18 is provided on one end of the slide 14 for manipulation of the same.

The reformer is generally referred to by numeral 21, while the cleaner is generally referred to by numeral 22.

The reformer and cleaner each comprise a pivoted arm of flat material, 23, in the case of the former and 29 in the case of the latter, pivotally mounted on the base 5 for swinging movement upwardly and downwardly toward and from the front face of the chuck 10, respectively, and hence toward and from a cap 20 positioned on said chuck. The pivotal mounting for said arms 23 and 29 comprises a pair of lugs 27, 28 for each arm upstanding from the base 5 and spaced in line laterally thereof, a pivot pin 26 extending through said lugs and hooked lower ends 23a and 30 on said arms 23 and 29, respectively, interposed between the lugs 27 and 28 and through which said pin 26 extends.

The upper end of the reformer arm 23 has rotatably mounted thereon a flat forming roller 36 adapted under upward swinging of said arms to be peripherally engaged with the inner face of the usual rim flange A of the jar cap 20. The

periphery of said roller 36 is outwardly beveled and concaved to reform said flange A into the usual cross sectional contour. A lever arm 34 is pivotally mounted on the reformer arm 23, as at 5 33, and provided with a handle 35 for manipulation of the same and a second flat former roller 37 is rotatably mounted on said lever arm, as at 10 39, for movement into and from peripheral clamping relation to the roller 36 under movement of the lever arm 34 in opposite directions, whereby said roller 37 may be moved into peripheral engagement with the outer face of 15 said flange A to clamp the latter between the same and the roller 36, as shown in Figure 5. The periphery of the roller 37 is inwardly beveled and convex so that said roller together with roller 36 will roll the flange A outwardly to prevent said flange from cutting the usual sealing ring (not shown) such as is associated with jar caps of the 20 Mason jar type. The lever arm 31 is provided with a slot 40 therein concentric to the pivot 33 and through which the axis member 41 of roller 36 extends, this arrangement providing against lateral play of lever arm 31 and roller 37.

25 As will be clear, the reformer arm 23, and the lever arm 34, together with the rollers 36 and 37 are movable as a unit about the pivot 26 toward the face of the flange A to position the roller 36 against the latter, whereas, the lever arm 31 is 30 swingable on the reformer arm 23 about an axis at a right angle to the pin 26 to position the roller 37 edgewise against flange A under upward movement of handle 35, said rollers being moved into straddling relation to the flange A by such upward swinging of said reformer arm. A handle 35 is provided on reformer arm 23 for manipulating the same and the handle 35 of lever arm 34 is positioned under the handle 35 for concurrent gripping of both handles by one hand of the 35 operator.

40 The cleaner arm 29 is provided with a handle 43 for manipulating the same and intermediate its ends with a bracket plate 44 to which is suitably secured the back 45 of a wire bristle brush 45 47 with the bristles extending laterally of the arm 29, the arrangement being such that under upward swinging of said arm 29 the bristles of said brush may be positioned in the cap 20 against the inner periphery thereof to clean the same.

50 Referring now to the operation, in reforming a cap 20, said cap is inserted, closed end foremost, in the chuck 10 between the clamping flanges 19 and the latter moved into clamping relation thereto by manipulation of the slide 14 in the 55 proper direction to cause the slots 16 and screws 17 to cam the wings 12 on the pivots 13 toward each other. The reformer arm 23 is next swung upwardly by means of handle 25 to locate roller 36 against the inside of flange A and lever 35

then pulled upwardly to move roller 37 against the outer side of flange A thereby clamping said flange between said rollers. With the handles 35, 25 firmly gripped by the hand of the operator to maintain the rollers 36, 37 in clamping engagement with flange A, the chuck 10 and cap 20 are rotated by operation of the crank 9, the rollers 36, 37 under such operation reforming the flange A circumferentially and transversely as will be clear. The manner in which the cap 20 is removed will be understood without explanation.

5 To clean the cap 20, the cleaner arm 29 is swung upwardly to locate the bristles of brush 46 in the cap and held in the proper position for this purpose. The cap 20 is now rotated with the 15 bristles 46 in wiping engagement with the inner periphery thereof.

20 While the foregoing specification sets forth the invention in specific terms, it is to be understood that numerous changes in the shape, size 20 and materials may be resorted to without departing from the spirit and scope of the invention as claimed hereinafter.

25 Having described the invention, what is claimed as new is:

1. In a device for reforming the edge flange of a jar cap, a base, an upstanding bearing bracket on said base, a shaft rotatably mounted in said bracket and having a crank on one end thereof for rotating the same, a chuck fast on the other 30 end of said shaft for rotation therewith and operative to clamp the cap thereto concentrically of said shaft, and flange reforming means comprising a pair of reforming rollers mounted on said base for movement bodily into and from 35 straddling relation to said flange and one movable independently of the other for cooperation with said other to clamp the flange therebetween during rotation of said cap.

2. In a device for reforming the edge flange 40 of a jar cap, a base, an upstanding bearing bracket on said base, a shaft rotatably mounted in said bracket and having a crank on one end thereof for rotating the same, a chuck fast on the other 45 end of said shaft for rotation therewith and operative to clamp the cap thereto concentrically of said shaft, and flange reforming means comprising an arm pivoted on said base for swinging movement toward and from said flange, a pair of reforming rollers movable bodily by such 50 movement of said arm into and from straddling relation to said flange, one of said rollers being mounted on said arm for movement independently thereof into and from clamping relation to the other roller during rotation of the cap, and 55 manipulative means for moving said independently movable roller at will.

MICHELANGELO DI GRAPPA.
